J. M. Mire

ATTORNEY

UNITED STATES PATENT OFFICE.

PIERRE KAPITZA, OF CHESTERTON, ENGLAND.

ELECTRIC HIGH-TENSION APPARATUS.

Application filed August 26, 1924, Serial No. 734,288, and in Great Britain September 5, 1923.

This invention relates to means for the production of high tension discharges of very high intensity.

In my Patent 1,656,203, granted Jan. 17, 5 1928, I have described an improved form of electric storage device adapted to give "single flash" discharges of very brief duration, but of very high amperage, the device being of comparatively small dimensions and readily 10 portable and capable of repeated short circuiting without damage.

It is an object of the present invention to provide means whereby such a device may be adapted to produce high tension 15 discharges.

A further object of the present invention is to provide an improved form of transformer adapted for use with "single flash" discharges through the primary of very high 20 intensity.

It is a further object of the present invention to provide improved means of comparatively small and portable dimensions for taking X-ray photographs.

25 It is a further object of the present invention to provide means for taking X-ray photographs with very brief exposures.

With these and other objects in view the invention will be fully described aided by the accompanying drawings, in which—

30 The figure is a wiring diagram illustrative of the process.

The figure illustrates a battery 1 giving a "single flash" discharge in accordance with 35 the description in my Patent 1,656,203, and connected on the one hand through an ammeter A and rheostat 4 to a suitable source of supply 2, 3, and on the other hand to the primary winding 5 of a transformer through 40 the intermediary of a switch 6, the secondary 9 of the transformer being connected to the spark gap 7, 8. Obviously, however, for X-ray work the secondary is connected to an X-ray tube at the points 7, 8.

45 It will be seen that normally the battery is charged from the source of electricity and on closing the switch 6 is discharged through the primary winding 5. This causes a secondary current of very high tension to be

generated in the secondary winding and a 50 discharge occurs across the gap 7, 8.

It is to be noted that the transformer is intended solely for use with flash discharges of the kind produced by the battery referred to in my Patent 1,656,203. In actual 55 use currents of 10 amperes at a tension of 40,000 volts were transmitted through the secondary through a Geissler tube, six of such flashes being sufficient to photograph the spectrum. In connection with ordinary 60 X-ray work, it was found possible to take satisfactory X-ray photographs with single flashes having a duration of from one-thousandth to five-thousandths of a second.

In use it is not necessary to break the primary circuit to obtain the high tension discharge as the duration of the primary flash discharge is so brief and in the absence of an inductive circuit is cut off so quickly 65 that the high tension discharge follows automatically on closing the primary switch.

70 It is to be understood, however, that the principal discharge in the secondary occurs when the primary switch is closed and not when the primary circuit is broken. Owing 75 to the large area of cross section of the armature an appreciable time (about one-hundredth of a second) is required for the magnetic saturation of the iron to occur and during this time the discharge occurs in the 80 secondary at practically constant e. m. f. which as stated above is a feature of importance in connection with X-ray work. In this connection, it is an important feature of the present invention that a high 85 tension discharge adapted for use in technical arts is obtained by discharging the contents of an accumulator through the primary of a transformer whereas hitherto such high tension discharges have only been 90 obtained in practice by breaking the primary current or using an alternating current.

I claim:—

95 1. A process of obtaining a high tension discharge at constant voltage, consisting in combining with a flash discharge accumulator, a transformer of the type having a closed iron core with low resistance in the

primary, the accumulator being continuously charged, and being discharged on make in the primary.

2. A process of obtaining a high tension discharge at constant voltage which consists in combining with a single flash accumulator, a transformer having a primary of few turns of low resistance, a secondary,

and a closed iron core of large cross section, a switch between the accumulator and primary, the accumulator being continuously charged, and being discharged on closing the switch. 10

In testimony whereof I affix my signature.

PIERRE KAPITZA.
